(57) **CLAIM**

The ornamental design for a pet toilet, as shown and described.

DESCRIPTION

FIG. 1 is a front perspective view of a pet toilet showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a sectional view of FIG. 7 taken along lines 9-9 in FIG. 7.

The broken lines in the drawings are for the purpose of illustrating portions of the pet toilet that form no part of the claimed design.

1 Claim, 8 Drawing Sheets
